(57) **CLAIM**

The ornamental design for an archery bow, as shown and described.

DESCRIPTION

FIG. 1 is a perspective view of the archery bow of the present invention;

FIG. 2 is the front view of the archery bow;

FIG. 3 is a left side view of the archery bow;

FIG. 4 is a rear view of the archery bow;

FIG. 5 is a right side view of the archery bow; and,

FIG. 6 is a top view of the bow of FIG. 1. The bottom view is identical to the top view.
